Des. 230,314
Patented Feb. 5, 1974

230,314

MICROFICHE READER

Hideto Furuoka, Tokyo, Japan, assignor to Gakken
Co., Ltd., Tokyo, Japan

Filed Nov. 6, 1972, Ser. No. 304,233

Claims priority, application Japan May 6, 1972

Term of patent 14 years

Int. Cl. D16—03

U.S. Cl. D61—1 N

FIG. 2

FIG.1

FIG.3

FIG.4

FIG.5

FIG.7

FIG.6

FIG.8

FIG. 1 is a front elevational view of a microfiche reader showing my new design;

FIG. 2 is a back elevational view thereof;

FIG. 3 is a right side elevational view thereof;

FIG. 4 is a left side elevational view thereof;

FIG. 5 is a top plan view thereof;

FIG. 6 is a sectional view taken along line 6-6 of FIG. 1;

FIG. 7 is a sectional view taken along line 7-7 of FIG. 1;

FIG. 8 is a front perspective view thereof.

I claim:

The ornamental design for a microfiche reader, substantially as shown and described.
